UNITED STATES PATENT OFFICE.

THOMAS HARDING, OF NEWARK, NEW JERSEY, ASSIGNOR TO J. L. SOMMER MANUFACTURING CO., A CORPORATION OF NEW JERSEY.

CLEANER FOR PIPES AND THE LIKE.

1,287,681.

Specification of Letters Patent.

Patented Dec. 17, 1918.

Application filed February 5, 1916. Serial No. 76,247.

To all whom it may concern:

Be it known that I, THOMAS HARDING, a citizen of the United States, and a resident of Newark, in the county of Essex and State of New Jersey, have invented certain new and useful Improvements in Cleaners for Pipes and the like, of which the following is a specification.

The objects of this invention are to provide a cleaner having pivoted scraping members with an extensive range of pivotal movement, so that they can adjust themselves to pipe bowls of varying shapes; to enable the pivotal movement to be predetermined and varied as desired; to employ for this purpose a scraping member of sheet metal having at its rear edge an ear of less length than the member returned parallel to the blade, so as to receive the handle member between said ear and blade; to thus provide by the edge of said ear a stop to engage the handle member and limit swing; to thus enable the swing to be determined by the width of the ear; to secure simplicity of construction and operation, and to obtain other advantages and results as may be brought out in the following description.

Referring to the accompanying drawings, in which like numerals of reference indicate the same parts throughout the several views,

Figure 1 is a side elevation of a pipe cleaner embodying my invention shown in operating position within a pipe sectioned through its bowl;

Fig. 2 is an edge view of such a pipe cleaner looking at the right hand edge as shown in Fig. 1;

Figs. 3 and 4 are perspective views of the scraping members, and

Fig. 5 is an elevation of the handle member from which the scrapers have been removed.

In the specific embodiment of the invention illustrated in said drawings, the reference numeral 1 indicates the body portion or handle member of my improved cleaner, the same preferably being a metallic spring loop 2 the ends of which are flattened in the plane of the loop as at 3, 4. These flattened portions or ends 3, 4 extend away from the loop, diverging somewhat, and being spaced apart so as not to interfere when in operation it becomes necessary for them to be pressed together. It will be understood that the loop is sufficiently resilient to per-

mit the ends to be thus pressed together and to spread them apart again as soon as they are released.

Adjacent the free ends of these flattened portions 3, 4 are pivoted scraping members 5, 6 flatwise with respect thereto so as to swing in the plane of the loop. Obviously the outer long edges of these scrapers form the cutting edges, and preferably one of these scrapers as 5, is provided with a plurality of teeth 7 longitudinally of its cutting edge so that as the scraper is turned around within a pipe bowl or the like the matter to be cleaned off is scraped by the teeth, leaving ridges between where the teeth have scraped. By this means the scraper is adapted to embed in the material much more readily than a smooth blade or blade without teeth, and will in any event break up a crust or coating with greater facility. The other scraping member 6 is preferably provided with a smooth cutting edge, that is, an edge without teeth or corrugations, and it will be understood in operation that as the device is turned around the smooth edge will scrape off the ridges left by the toothed scraper.

Preferably the scrapers are positioned upon opposite sides of the flattened portions of the handle member, and in such manner that as the device is held in upright position the scraper toward the right hand side will be mounted upon the front of the handle member and the scraper at the left hand side will be mounted upon the back of the handle member. By this construction, it will be observed that as the device is rotated in a right hand direction, as would ordinarily be done, the scrapers will be in front of the supporting portions of the handle member and will push the dirt scraped off around ahead of them and thus prevent as far as possible the tendency of dirt to enter between the scrapers and their supporting portions of the handle. Furthermore, it will be observed that a considerable portion of the length of the scraper is in flatwise engagement with the flattened portion of the handle, so the handle will push the scraper around without any tendency to pull it off of its pivotal support, and will also reinforce the scraper so it will not become bent.

Preferably, in order to strengthen the scrapers, the same are provided with ears 8, 9 upon their inner edges which are turned back each to overlie the body portion of the

scraper substantially parallel thereto in spaced relation, so that the flattened portions of the handle may be inserted and pivoted therebetween as by rivets 10, 11. These ears 5 are of less width than the length of the scraper members, and provide at their upper edges stops to engage the handle ends and limit swinging, so that by the width of the ears the swing of the scraper members is 10 predetermined. It will be noted that by making the ears narrow in comparison to the length of the scraper members considerable swing of said members is secured, even so that their upper ends clear the handle ends 15 3, 4. As shown in the drawings, the inner edges of the flattened portions are notched as at 12, 13 to permit the scrapers to tilt outward at their upper ends, the notches accommodating the portions of the ears connecting 20 the body of the scrapers to the parts of the ears which are parallel thereto.

It will be noted that by this construction the thickness of the device is substantially that of the metal forming the loop of the handle, so that the same is flat and very 25 readily carried in a pocket and not likely to become caught or injured. The parts are simple and readily made from sheet metal and the scrapers will operate without themselves becoming clogged. 30

While I have illustrated a form of my cleaner especially adapted for scraping the

interior surface of the bowls of smoking pipes, I do not wish to restrict myself in any way to this use of my invention, and it will 35 be understood that the construction set forth can be employed in cleaners for any purpose to which the invention can be utilized. Furthermore, various detail modifications and changes may be made in manufacturing my 40 improved cleaner without departing from the spirit and scope of the invention and I do not wish to be understood as restricting myself except as required by the following claim when construed in the light of the 45 prior art.

Having thus described the invention, what I claim is.

In a device of the character described, the combination with a handle member having 50 an end adapted to enter a pipe bowl, of a scraper having a blade at one side of said handle member and an ear of less width than the length of said blade projecting from the rear edge of the same around the said end of 55 the handle member and turned forwardly parallel to the blade, and a pivot through said ear, handle member and blade, whereby the blade can swing with respect to the handle member and yet a positive stop is provided by the edge of the ear which can be positioned as desired by determining the 60 width of the ear.

THOMAS HARDING.
